UNITED STATES PATENT OFFICE.

ALFRED M. REMINGTON, OF FITCHBURG, MASSACHUSETTS, ASSIGNOR TO SIMONDS MANUFACTURING COMPANY, OF FITCHBURG, MASSACHUSETTS, A CORPORATION OF MASSACHUSETTS.

ATTACHMENT FOR SAW-FRAMES.

1,194,234.

Specification of Letters Patent.

Patented Aug. 8, 1916.

Application filed March 30, 1916. Serial No. 87,703.

To all whom it may concern:

Be it known that I, ALFRED M. REMINGTON, a citizen of the United States of America, residing at Fitchburg, in the 5 county of Worcester and State of Massachusetts, have invented an Improvement in Attachments for Saw-Frames, of which the following is a specification.

The invention relates to attachments for 10 saw frames, more particularly for skeleton frames such as employed for hack-saws, to facilitate their better manipulation, and it consists of a forked portion to extend over and embrace the frame bar, with means such 15 as a screw to pass through the two branches of the fork and clamp it to the frame bar, a lug or finger extending substantially parallel to the branches of the fork, and engaging the frame bar in opposition to the clamping 20 means, and a thumb rest extending out from the attachment to aid in maintaining a firm grip upon the saw frame and facilitate its manipulation.

In the drawings forming a part of this 25 specification,—Figure 1 is a side elevation of a saw-frame, with the gripping attachment secured thereto at the forward end;

Fig. 2 is an enlarged detail of the attachment secured to the frame bar; and Fig. 3 is an end elevation of the attachment, removed 30 from the frame and viewed from the right of the position shown in Fig. 2.

Referring to the drawings by designating letters, A is the thumb rest of the attachment, B is a projecting lug which rests against 35 the saw frame E in opposition to the two branches of the fork C which embrace the saw frame and are clamped thereon by a bolt or screw which passes through the ends of the two branches thereof and against the 40 side of the frame opposite to the lug B, and when the bolt is screwed up tight the attachment will be held firmly in place on the frame. Its position may be adjusted to suit 45 the user.

I claim:—

An attachment for saw frames consisting of a forked portion to embrace the frame bar, means to clamp the forked portion to the frame, a projecting lug to engage the 50 frame in opposition to said clamping means, and a thumb rest extending outward from the attachment.

ALFRED M. REMINGTON.
